UNITED STATES PATENT OFFICE.

CORNELIUS VANDERBILT, JR., OF NEW YORK, N. Y.

LOCOMOTIVE-BOILER.

SPECIFICATION forming part of Letters Patent No. 637,186, dated November 14, 1899.

Application filed January 27, 1899. Serial No. 703,572. (No model.)

To all whom it may concern:

Be it known that I, CORNELIUS VANDERBILT, Jr., of the city of New York, borough of Manhattan, in the county and State of New York, have invented a new and Improved Locomotive-Boiler, of which the following is a full, clear, and exact description.

The object of the invention is to provide a new and improved locomotive-boiler arranged to materially increase the strength of the boiler, to resist all strain due to expansion and contraction of the parts or other causes, and to avoid rupture of the sheets, the arrangement also giving a more effective heating-surface, notably in the fire-box, to insure a rapid generation of steam.

The invention consists of novel features and parts and combinations of the same, as will be fully described hereinafter and then pointed out in the claims.

A practical embodiment of my invention is represented in the accompanying drawings, forming a part of this specification, in which similar characters of reference indicate corresponding parts in all the views.

Figure 1 is a longitudinal central sectional elevation of the improvement. Fig. 2 is an enlarged end elevation of the same. Fig. 3 is an enlarged transverse section of the same on the line 3 3 in Fig. 1. Fig. 4 is a like view of the same on the line 4 4 in Fig. 1, and Fig. 5 is a similar view of the same on the line 5 5 in Fig. 1.

The shell of the locomotive-boiler is provided with a barrel or outer section A, disposed horizontally and made cylindrical and having a smoke-box A' projecting from the outer end of the barrel. The rear end of the barrel is connected with the small end of the wagon-top A² in the form of a cone, the rear or base end being connected with a fire-box section A³, inclined rearwardly and downwardly from said wagon-top A², as is plainly indicated in Fig. 1.

The section A³ is made cylindrical in cross-section, as is plainly indicated in Figs. 2 and 3, and in said section is arranged eccentrically a fire-box B, likewise made cylindrical in cross-section, the rim or wall of said fire-box being corrugated in a transverse direction, as is plainly indicated in Fig. 1. The forward end of the fire-box B is suspended by links C

from the forward top portion of the fire-box section A³, the lower or bottom portion of the fire-box resting on suitable supports C', carried by the section A³, as illustrated in Fig. 3. The open end of the fire-box B is riveted or otherwise secured to the front sheet A⁴ of the fire-box section A³. (See Fig. 1.)

The flues E extend from the fire-box flue-sheet B' to the flue-sheet F, formed with a rim having transverse corrugations F', as is plainly shown in Fig. 1, the corrugations extending a suitable distance from the inner surface of the barrel A to permit a proper yielding in a longitudinal direction of the flue-sheet upon expansion and contraction of the flues E to relieve the barrel A of undue strain, it being understood that the extreme outer end of the corrugated sheet is riveted in the usual manner to the barrel or outer section A.

By the arrangement described the flues E stand at an angle to the axis of the barrel A and the wagon top A², and the flue-sheet F stands at an angle to the outer end of the barrel—that is, is inclined to the vertical—as is plainly indicated in Fig. 1, and by tilting the fire-box B the water-space below the fire-line at the back is reduced to increase the depth above the fire-line, thus giving a more effective heating-surface in the back end portion of the fire-box. By not submerging the forward end to the same extent that the rear end is submerged a still more effective heating-surface is obtained, thereby insuring a rapid generation of steam. It is further evident that by the arrangement described, especially by the cylindrical form of fire-box and barrel, the strength of the boiler is materially increased and a rupture of the sheets is not liable to take place, as unequal strains are avoided, and the connection and form of the several sections are such as to resist all strain due to expansion and contraction of the various parts and to the pressure of the generated steam.

Having thus fully described my invention, I claim as new and desire to secure by Letters Patent—

1. A locomotive-boiler, provided with a fire-box made cylindrical in cross-section and having its rim or wall corrugated in a transverse direction, and a fire-box section in which the fire-box is placed eccentrically, the axis of

the fire-box section being inclined to the horizontal, to reduce the water-space below the fire-box line at the back end of the fire-box, and the forward end of said fire-box being 5 submerged to a less extent than the rear end, to increase the effective heating-surface for a rapid generation of steam, substantially as shown and described.

2. A locomotive-boiler comprising a shell 10 having a horizontally-disposed barrel-section, a conical wagon-top, a fire-box section inclined downwardly and rearwardly from the base of the said conical wagon-top section, a fire-box hung eccentrically in said fire-box 15 section and with its axis inclined to the horizontal, an inclined flue-sheet in the barrel-section, and flues extending from the front end of the fire-box to the said flue-sheet and approximately at right angles thereto, sub- 20 stantially as shown and described.

3. A locomotive-boiler comprising a horizontally-disposed barrel-section, a conical wagon-top section, a cylindrical fire-box section inclined downwardly and rearwardly 25 from the base of said wagon-top section, a fire-box made cylindrical in cross-section and having its wall or rim corrugated in a trans-

verse direction and hung eccentrically in the said fire-box section, a flue-sheet in the said barrel-section, and inclined flues extending 30 upwardly and forwardly from the front of the fire-box to the said flue-sheet, substantially as shown and described.

4. In a steam-boiler, the shell comprising a horizontally-disposed cylindrical barrel, a 35 conical wagon-top in axial alinement with the barrel and a cylindrical fire-box section in combination with a cylindrical fire-box eccentrically disposed in the said fire-box section and secured thereto at its open entrance 40 end, and flues extending from the forward closed end of the said fire-box in an upward and forward direction to connect with the flue-sheet in the said barrel, substantially as shown and described.

5. In a steam-boiler, a cylindrical fire-box section, and a cylindrical fire-box eccentrically mounted in the said fire-box section and inclined thereto in a longitudinal direction, substantially as shown and described.
